DAVIT

Claude J. Boudreau, Medford, Mass.

Application November 26, 1937, Serial No. 176,483

5 Claims. (Cl. 9—22)

This invention relates to a davit or the like device useful not only for launching small boats and the like, but also for shifting, discharging or taking on various types of cargoes.

5 In using watercraft such as small yachts, sloops, motor boats, etc., it is frequently desirable to carry along a tender, such as a dinghy, and it is usually necessary to carry the tender in tow due to the difficulties involved in launching and stowing. Although davits and the like structures may be used on large-sized boats, the design of the hull or superstructure of small watercraft is such as to prohibit the use of davits of conventional construction.

10 The principal objects of the present invention are to provide a davit or the like device which may be used on small watercraft and to provide a device which may be set up for use alone or in conjunction with one or more similar devices, 20 and which may be collapsed into a self-contained or nested unit adapted to lie substantially flat on the deck of the boat.

15 Further objects will be apparent from a consideration of the following description and accompanying drawings, wherein:

Figs. 1 and 2 are side and top plan views of a boat provided with davits constructed in accordance with the present invention;

25 Fig. 3 is a side elevation of one embodiment of the invention in erected position;

30 Fig. 4 is an enlarged fragmentary top plan view, with parts broken away, showing the davit in collapsed position;

35 Fig. 5 is a longitudinal section through the parts shown in Fig. 4;

Fig. 6 is an enlarged section on the line 6—6 of Fig. 3;

Fig. 7 is an enlarged section on the line 7—7 of Fig. 3;

40 Fig. 8 is a view similar to Fig. 3 but showing a modified embodiment of the invention;

Fig. 9 is an enlarged fragmentary longitudinal section through the carriage, illustrating one type of locking device;

45 Fig. 10 is a view similar to Fig. 3 but showing another embodiment of the invention;

Fig. 11 is an enlarged side elevation of the carriage member of the embodiment shown in Fig. 9;

50 Fig. 12 is a fragmentary top plan view of the bow of a boat provided with a davit of the type shown in Fig. 10;

Fig. 13 is a view similar to Fig. 12, but illustrating a davit pivotally secured at its rear and also

a curved davit extending along the upper edge of the bow; and

Fig. 14 is a front elevation of a boat provided with a davit made in accordance with the present invention and illustrating its use in launching a 5 dinghy.

Referring to Figs. 3 to 7 inclusive, the embodiment therein shown comprises an elongate channel-like base member 1 having spaced upstanding sides 2 and 3 which are formed with inwardly extending flanges 4 and 5, as shown in Fig. 6. The ends of the base member are preferably cut at an angle and provided with closure plates 6 (Fig. 3). The base member and other parts herein-after described are preferably made of rustproof 10 stock, such as high chromium steel, bronze, or the like, and where the device is designed for use on a boat having a curved or crowned deck, the base member is curved longitudinally to conform with the contour of the deck, as illustrated 15 in Fig. 3. In order to secure the base member in position it may be provided with a plurality of spaced laterally extending ears 8 (Fig. 3) or, if desired, the bottom of the base member may be provided with a series of openings 9 (Fig. 6). In 20 either case the base member may be firmly secured to the deck or superstructure of a boat, as illustrated in Figs. 1 and 2.

Mounted within the confines of the sides 2, 3 and flanges 4, 5 of the base member is a carriage 30 10, here shown as comprising a pair of spaced longitudinally extending bars or rails whose opposite ends 11 and 12 are provided with aligned openings which receive an axle 15 and stub shafts 16, respectively (Figs. 4 and 5). Wheels or rollers 35 17 are mounted on the axle 15 and rollers 18 are mounted on the stub shafts 16, the parts being so constructed and arranged that a slight clearance is provided between each of the rollers and sides 2, 3 and flanges 4, 5, as illustrated in Figs. 5 40 and 6.

One end of an elongate hoisting beam 20, here shown as a tubular member curved longitudinally to conform with the curvature of the base member 1, is pivotally mounted on the axle 15, and a 45 brace member 22, integral with the stub shafts 16, is pivotally supported at the opposite end of the carriage. Since the free end of the beam is designed to overlie the brace when the parts are in nested position, the pivotally mounted end of the 50 brace is formed with a recess 21 (Fig. 4) to accommodate the undersurface of the beam. In the construction here shown the pivotally mounted ends of the beam and brace may provide spacers for holding the body and ends of the carriage 10 55

in position, although, if desired, a U-shaped element 24 (Fig. 4) may be provided to serve not only as a spacer, but also as a reinforcement, it being understood that the particular construction of the carriage and associated parts may be varied as long as the requisite degree of strength and rigidity is provided. The length of the beam 20 is slightly less than that of the base 1 and its free end is provided with a loop, hook or the like 23 to support a pulley or block and tackle, as shown in Fig. 14.

A sleeve or collar 25 is slidably mounted between the ends of the beam 20 and its under-surface preferably is dovetailed or otherwise shaped to provide an interlocking engagement with the free end of the brace 22, as shown in Fig. 7. The upper surface of the sleeve 25 is integral with a cleat 26 which is useful not only in securing the tackle during manipulation of the carriage, but also to provide means to which a tow line or the like may be attached when the device is in collapsed or nested position (Fig. 5). The sleeve 25 may have a tight sliding fit about the beam 20 in which case no fastening elements may be required to hold it in position, but if desired, a set screw 28 (Fig. 7) or like fastening element may be provided to hold the sleeve in any of a plurality of positions engageable with the free end of the brace 22.

The parts are so constructed and arranged that when the carriage 10 is disposed at one end of the base, the brace 22 may be swung or folded against the base and the beam 20 swung downwardly between the sides 2 and 3, as shown in Figs. 4 and 5, in which position both the beam and brace are nested within the base member. When thus collapsed the entire device takes up a minimum of space on the deck of the boat, and not only has the appearance of but also serves 40 as a reinforcing rib on the deck or cabin of the boat.

When using the device it is merely necessary to swing the beam 20 and brace 22 upwardly from collapsed position so that the free end of the brace may be interlocked with the sleeve 25. When thus erected a pulley or block and tackle may be secured to the loop 23 and the carriage slid along the base member so that the beam is in operative position. For example, if it be desired to launch a dinghy or discharge a cargo over the side of the boat, one end of the tackle may be secured about the dinghy or cargo and then sufficient tackle drawn in to suspend it in midair, after which the carriage may be slid along the base so that the load carried by the beam clears the side of the boat and then the tackle may be let out, as illustrated in Fig. 14, and while maneuvering the carriage, the tackle may be secured about the cleat 26. In order to take on and stow a dinghy or cargo, the procedure is simply reversed.

The davit shown in Fig. 8 is substantially identical in all material particulars with that shown in Fig. 3, and the same or similar reference characters are applied to corresponding parts. As this particular type of davit is designed to be secured to a substantially flat deck of a boat, as indicated at 1^a in Figs. 1 and 2, the base member 1^a is straight, rather than curved. As it may be desirable to lock the carriage at some point along the base member, any suitable type of carriage lock may be provided. As here shown by way of illustration, the carriage lock may comprise a U-shaped member 30 (Figs. 8 and 9) interposed between the rails 10 and having its open

end or legs pivotally secured thereto so that its closed end may be swung from an upstanding position to a substantially horizontal or locking position. The legs of the member 30 are formed with cam-like noses 31 constructed and arranged 5 to engage the base member when the closed end is swung to horizontal position, thereby providing a friction lock which prevents the carriage from being moved. If desired, a ring 32 or other suitable pull member may be secured to the closed 10 end so as to provide a convenient means for quickly releasing the carriage lock.

In Figs. 10 and 11 I have shown another modification which is designed to permit a greater degree of adjustment. In this embodiment the base 1^b is shaped to conform to the contour of its supporting surface, the parts being substantially the same as in the previously described embodiment. The carriage 10^b is of somewhat different construction in that it consists of a cast- 20 ing formed with an upstanding stub shaft 33 which rotatably supports a collar 34 to which the lower end of the beam 20^b is pivotally secured, as shown in Fig. 11. The ends of the carriage 10^b are provided with openings which receive axles 25 on which are mounted rollers 17 and 18 for supporting the carriage for movement longitudinally of the base. The beam 20^b may be of U-shaped cross section, and a brace 22^b (Fig. 10) is pivotally secured to the beam to hold it in any of a 30 plurality of upstanding positions. The lower end of the brace preferably is formed with a pointed end adapted either to project into openings or recesses formed in the base member or to bite into the deck of the boat or other supporting surface. 35 With this particular construction the beam is mounted for universal pivotal movement relative to the base member and where, as shown in Figs. 1, 2, 12 and 13, the base member is secured to the bow of the boat, the beam may be manipulated so as to operate at both the port and starboard sides adjacent to the bow. If desired either the front or rear end of the base member may be pivotally secured to the deck so that the entire device may be swung from one position to another, as indicated by the dot and dash lines of 40 Figs. 12 and 13.

In Fig. 13 I have also illustrated a davit having a base member 1^d which is curved to conform with the curvature of the bow of the boat, in which case the beam and brace members have a curvature conforming to that of the base member, otherwise the parts may be substantially identical to those above described. Such a davit may be disposed closely adjacent to the edge of 50 the deck and, if desired, this type of davit, as well as the types above described, may be built into 55 the deck so that the upper surface of the base member is substantially flush with the surface of the deck.

A davit constructed in accordance with the present invention and having a length of the order of six feet may be built so that its gross weight is approximately seventy-five pounds or less and its carrying capacity four hundred pounds or more. Such a davit may be operated by a single person without difficulty and, if desired, the davit may be used alone, as above described, or in conjunction with one or more similarly constructed davits, in which case the davits 70 are preferably arranged in pairs 1, 1^a, etc., as illustrated in Figs. 1 and 2. A single davit disposed at the bow of the boat, as illustrated in Figs. 1, 2, 12 and 13, is particularly useful in pulling an anchor, and as the end of the beam 75

projects outwardly beyond the bow, there is no danger of the anchor scarring or injuring the finish of the boat.

While I have shown and described different desirable embodiments of the invention, it is to be understood that the present disclosure is for the purpose of illustration and that various changes in shape, proportion, and arrangement of parts, as well as the substitution of equivalent elements for those herein shown and described, may be made without departing from the spirit and scope of the invention as set forth in the appended claims.

I claim:

1. A collapsible self-contained davit adapted for use on small watercraft, comprising an elongate base having spaced upstanding side walls, an elongate carriage supported at opposite ends for movement along said base member, locking means carried by said carriage for holding it in any position along said base, a hoisting beam pivotally secured to said carriage, and a brace engageable with said hoisting beam for supporting it in an upstanding position, said brace and beam being pivotally supported so as to be folded to lie substantially within the confines of said side walls, thereby to provide a compact assemblage substantially free from projecting parts.

2. A collapsible self-contained davit adapted for use on small watercraft, comprising an elongate base having spaced upstanding side walls, an elongate carriage supported at opposite ends for movement along said base member, a hoisting beam pivotally secured to one end of said carriage, and a brace pivotally secured to the opposite end of said carriage, the free end of said brace being engageable with said hoisting beam for supporting it in an upstanding position, said brace and beam being pivotally supported so as to be folded to lie substantially within the confines of said side walls, thereby to provide a compact assemblage substantially free from projecting parts.

3. A collapsible self-contained davit adapted for use on small watercraft, comprising an elongate base having spaced upstanding side walls, an elongate carriage supported at opposite ends for movement along said base member, locking means carried by said carriage for holding it in

any position along said base, a hoisting beam pivotally secured to said carriage, a collar slidably mounted on said beam so as to move longitudinally thereof, means for holding said collar in fixed position relative to said beam, and a brace pivotally supported on said carriage and engageable with said collar to support said beam in any of a plurality of upstanding positions, said brace and beam being pivotally supported so as to be folded to lie substantially within the confines of said side walls, thereby to provide a compact assemblage substantially free from projecting parts.

4. A collapsible self-contained davit adapted for use on small watercraft, comprising an elongate base having spaced upstanding side walls and inwardly directed retaining flanges, said base being shaped to conform with the contour of the surface to which it is designed to be secured, an elongate carriage having at its ends rollers positioned beneath said flanges for supporting said carriage for movement longitudinally of said base, a hoisting beam pivotally secured to said carriage, and a brace engageable with said hoisting beam for supporting it in an upstanding position, said brace and beam being pivotally supported so as to be folded to lie substantially within the confines of said side walls, thereby to provide a compact assemblage substantially free from projecting parts.

5. A collapsible self-contained davit adapted for use on small watercraft, comprising an elongate base having spaced upstanding side walls, said base member being shaped to conform with the contour of the surface to which it is designed to be secured, an elongate carriage having at its ends transversely extending axles, rollers mounted on said axles and supporting said carriage for movement along said base, a hoisting beam pivotally supported by one of said axles, and a brace pivotally supported by the other of said axles, the free end of said brace being engageable with said hoisting beam for supporting it in an upstanding position, said brace and beam being pivotally supported so as to be folded to lie substantially within the confines of said side walls, thereby to provide a compact assemblage substantially free from projecting parts.

CLAUDE J. BOUDREAU.
